UNITED STATES PATENT OFFICE

HERMAN KRUPP, OF SEATTLE, WASHINGTON

DESIGN FOR A WATCH CHARM OR SIMILAR ARTICLE

Application filed February 13, 1931. Serial No. 38,648. Term of patent 3½ years.

To all whom it may concern:

Be it known that I, HERMAN KRUPP, a citizen of the United States, residing at Seattle, in the county of King and State of Washington, have invented a new, original, and ornamental Design for Watch Charm or Similar Article, of which the following is a specification, reference being had to the accompanying drawing, forming a part thereof.

In the drawing:

Fig. 2 is a top plan view of the watch charm showing my new design.

I claim:

The ornamental design for a watch charm or similar article, as shown.

HERMAN KRUPP.
